COMBINED NOVELTY MIRROR AND WHISK BROOM

Ernest Steiner, New York, N. Y.

Application January 17, 1951, Serial No. 13,835

Term of patent 7 years

(Cl. D9—2)

To all whom it may concern:

Be it known that I, Ernest Steiner, a citizen of the United States, and a resident of the city, county, and State of New York, have invented a new, original, and ornamental Design for a Combined Novelty Mirror and Whisk Broom, of which the following is a specification, reference being had to the accompanying drawings, forming part hereof, and in which:

Fig. 1 is a front elevational view of a combined novelty mirror and whisk broom, showing my new design.

Fig. 2 is a rear elevational view.

Fig. 3 is a side elevational view of the left side of Fig. 1.

Fig. 4 is a side elevational view from the right side of Fig. 1.

Fig. 5 is a top elevational view.

The mirror surface in Fig. 2 is shaded to show transparency.

I claim:

The ornamental design for a combined novelty mirror and whisk broom, substantially as shown and described.

ERNEST STEINER.
